(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface, showing our new design.

The boundary line shown in dot-dash form indicates the bounds of the claimed design. It is understood that the claimed design extends to the boundary line but does not include the boundary line.

The outermost evenly dashed broken line in the FIGURE indicates a display screen or portion thereof, which forms no part of the claimed design.
